UNITED STATES PATENT OFFICE

GEORGE P. JACKSON, OF FLUSHING, NEW YORK, ASSIGNOR TO INTERNATIONAL COMBUSTION ENGINEERING CORPORATION, OF NEW YORK, N. Y., A CORPORATION OF DELAWARE

BOILER FURNACE

Application filed November 6, 1925. Serial No. 67,384.

My invention relates to boiler-furnaces, and is particularly useful in the burning of pulverized fuel. Primarily it contemplates an arrangement of parts whereby it is possible to use pulverized fuel where heretofore it has not been possible.

Another object of the invention is to make it practically feasible to burn pulverized coal in a boiler setting with horizontal admission of the fuel.

10 A further object of the invention is the provision of a novel arrangement of furnace and boiler construction having a very large proportion of the area of the evaporating 15 surfaces exposed to radiant heat, with, at the same time, a comparatively short travel of the fuel and flame stream.

Still another object of the invention is the provision of novel means for supplying 20 highly preheated air to hasten ignition and support rapid combustion of the fuel.

How I obtain these advantages, and others which will occur to those skilled in the art, will clearly appear hereinafter and 25 by reference to the accompanying drawings. Figure 1 is a vertical longitudinal section of a boiler-furnace embodying my improvements, certain of the associated parts being illustrated somewhat diagrammatically.

30 Figure 2 is a fragmentary vertical cross section taken on the line 2-2 of Figure 1. The combustion chamber, designated by the reference character L, is substantially of L shape, and the fuel is admitted thereto substantially horizontally in the horizontal leg of the L through the burner nozzle or nozzles 2, to which it is fed from the bin or hopper H, by the usual aerating feeder (shown diagrammatically at 3) and the conduit 4.

35 The front or upper, and back or lower, sides of the L-shaped combustion space are defined by rows of upcomer tubes 5 and 6 connected into the circulation of the boiler 40 unit B, the tubes 5 being connected to the

drum 7 and the tubes 6 extending into and discharging near the top of drum 8. At their lower ends the tubes 5 are connected to a transverse header 9 and the tubes 6 to a similar header 10, the two headers being 50 connected by suitable pipes 11. At each end of the header 10 is connected a large downcomer tube 12, these tubes being located outside the furnace walls and connected at their upper ends to the lower part of the 55 drum 8. The tubes 5 and 6 are spaced laterally, and carry, at their adjacent sides, fins 13 and 14 of the proper width to close the gaps between tubes. Along the lower portions of the tubes 5 and 6 however, the 60 fins 13 and 14 are broken away at intervals to leave air inlets or passages 15 and 16 between the tubes. The tubes 17, of the boiler unit B, may also be equipped with fins, these fins 18 closing the gaps between tubes 65 for a portion of the length of the tubes to provide baffles around which the gases of combustion must pass. However, these fins may be dispensed with entirely and a single 70 pass employed, as this section of the boiler is largely of the convection type, and functions, with the exception of the lowermost row of tubes, somewhat after the nature of an economizer.

75 Located rearwardly of the boiler is an air-preheater P, through which the gases, while still at a high temperature, must pass on their way to the offtake 19 leading to the usual stack (not shown). Air for combustion, forced through the preheater by the 80 fan F, is delivered through the conduits 20 and 21 to the upper and lower air-spaces or chambers 22 and 23, from which it enters the furnace chamber L through the passages 15, 16. The space 23 is of sufficient vertical 85 depth to permit of the accumulation of the solid refuse products of combustion on the floor 24, and in the front wall there is provided a convenient cleanout door 25 for such refuse. As some of the ash, however, will 90

settle upon the tubes 6 and on the sections of the fins 14 between the openings or inlets 16, it will be necessary from time to time to clean off such ash deposit, and for this purpose there is provided a door 26 through which a steam or air lance may be directed to dislodge the deposit and precipitate it, through the openings 16, to the floor 24.

In operation this boiler furnace is characterized by a short, hot flame, and by the exposure to its radiant heat of a large area of the evaporating surfaces. This arrangement produces enough steam in the tubes 5 and 6 to permit of the employment of a relatively small boiler proper, the setting here shown utilizing only a single boiler unit B, the tubes of which are very short, and few in number. In consequence of the combination of violent combustion, short travel of the fuel and flame stream, and small size of the boiler proper, the waste gases pass to the air heater P at an unusually high temperature. The result is a very great degree of preheat. This highly preheated air, forced through the conduits 20 and 21 by the fan F, discharges from above and below the horizontal leg of the L-shaped fuel and flame stream through the ports or openings 15, 16, violently agitating the incoming stream of fuel and air as it enters the furnace, and initiating and supporting a very hot flame by reason of such agitation and consequent commingling of the fuel with the highly heated air.

By virtue of the fact that there is so much evaporating surface subject to radiant heat, heat is transmitted to the boiler at a very high rate and consequently, as before mentioned, for the same steaming capacity a very small boiler can be employed as compared to standard practice. Because of the turbulence of combustion and the short flame obtained, and since the rear wall and the arch are protected by the tubes 6 and 5, horizontal firing of the fuel may be employed, with the fuel admitted well down toward the lower portion of the chamber. I am enabled to lower the arch 27 from a point usually near the level of the upper boiler down to a point more than halfway down if desired. Thus it is possible to locate the bin H, of the indirect firing system employed, immediately above the arch and in front of the setting. From the standpoint both of horizontal area covered and vertical height required the whole installation is very compact and may be housed in a relatively small building, whereby the initial plant investment is greatly reduced.

I claim:—

1. A boiler-furnace for burning pulverized fuel comprising, in combination, an L-shaped combustion chamber having a relatively horizontally shallow upright leg

and evaporating tubes marginal of the combustion space comprehended by the legs, an offtake at the upper portion of the combustion chamber for the products of combustion, a relatively short single bank of boiler tubes extending across said offtake, and means for admitting fuel horizontally into the lower portion of the combustion space to be burned in space therein. 70

2. A boiler-furnace for burning pulverized fuel comprising, in combination, an L-shaped combustion chamber having a relatively horizontally shallow upright leg and evaporating tubes marginal of the combustion space comprehended by the legs, an offtake at the upper portion of the combustion chamber for the products of combustion, a relatively short single bank of boiler tubes extending across said offtake, interrupted longitudinal fins on tubes of 80 said evaporating tubes providing openings for the admission of air into the lower part of said combustion chamber, and means for admitting fuel horizontally into the lower portion of the combustion space to be 85 burned in space therein. 90

3. A boiler-furnace for burning pulverized fuel comprising, in combination, an L-shaped combustion chamber having a relatively horizontally shallow upright leg, an offtake at the top for the gaseous products of combustion, a relatively short single bank of boiler tubes extending across said offtake, evaporating tubes marginally defining the front and rear of the upright portion of 95 said combustion chamber and the top and bottom of the lower portion of said chamber, longitudinal fins on said tubes, said fins being interrupted at intervals along those portions of the tubes which define said top and bottom to form openings for the admission of combustion air, and means for admitting fuel horizontally into the lower portion of the combustion space to be 100 burned in space therein. 105

4. A boiler-furnace for burning pulverized fuel, comprising, in combination, an L-shaped combustion chamber having a relatively horizontally shallow upright leg, an offtake at the top for the gaseous products of combustion, a relatively short single bank of boiler tubes extending across said off-take, evaporating tubes marginally defining the front and rear of the upright portion of 110 said combustion chamber and the top and bottom of the lower portion of said chamber, longitudinal fins on said tubes, said fins being interrupted at intervals along those portions of the tubes which define said top and bottom to form openings for the admission of combustion air, refractory sheathing providing an air chamber above the evaporating tubes which define the top of the lower portion of the combustion chamber and an air chamber below the evaporating tubes 115 120 125 130

which define the bottom of the lower portion of the combustion chamber, means for admitting preheated air to said chambers, and means for admitting fuel horizontally into the lower portion of the combustion space to be burned in space therein.

5. A boiler-furnace for burning pulverized fuel comprising, in combination, a furnace chamber having refractory side walls and an offtake at the top for the gaseous 10 products of combustion, a relatively short boiler having a single bank of tubes near the top of the chamber and two rows of L-shaped tubes connected into the circulation defining with the refractory side walls of 15 the chamber an L-shaped combustion space, and air chamber below the horizontal leg of the combustion space, means for admitting preheated air into said air chamber, said air being admitted to the combustion 20 space between the L-shaped tubes, and means for admitting fuel at the foot of the combustion space.

6. A combustion chamber having spaced 25 substantially horizontal tubes extending in the lower portion and above the bottom thereof, horizontally extending fins on said tubes; the tubes being so spaced and the fins being of such size that the fins of adjacent 30 tubes substantially abut, said fins being interrupted to provide openings for the admission of combustion air between the tubes, and means for admitting fuel to be burned in space.

35 7. A combustion chamber having spaced substantially horizontal tubes extending in the lower portion and above the bottom thereof, horizontally extending fins on said tubes, the tubes being so spaced and the fins being of such size that the fins of adjacent 40 tubes substantially abut, said fins being interrupted to provide openings for the admission of air between the tubes, means for admitting preheated combustion air below the tubes and means for admitting pulverized 45 fuel to be burned in space.

8. A boiler-furnace for burning pulverized fuel, comprising, in combination, an L-shaped combustion chamber, an offtake in the upper part thereof for the gaseous 50 products of combustion, evaporating tubes marginally defining the top and bottom of the horizontal leg of the combustion chamber, said tubes being spaced apart for the admission of combustion air, means providing an air chamber above the evaporating tubes which define the top of said leg, and an air chamber below the evaporating tubes which define the bottom of said leg, 55 means for admitting air to said chambers, and means for admitting fuel horizontally into said leg to be burned in space in the combustion chamber.

9. A boiler-furnace for burning pulverized fuel, comprising, in combination, a com-

bustion chamber having an arch-portion and an offtake in the upper part thereof, evaporating tubes at the arch portion arranged and spaced therefrom to provide an air chamber, said tubes being spaced apart 70 for the admission of combustion air, means for admitting air to said chamber, and means for admitting pulverized fuel into the combustion chamber below the arch.

In testimony whereof, I have hereunto 75 signed my name.

GEORGE P. JACKSON.
